UNITED STATES PATENT OFFICE.

HENRY FREDRICK COOMBS, OF CHARLOTTETOWN, PRINCE EDWARD ISLAND, CANADA.

BUTTER-TUB.

SPECIFICATION forming part of Letters Patent No. 289,390, dated December 4, 1883.

Application filed October 5, 1882. (Model.)

To all whom it may concern:

Be it known that I, HENRY FREDRICK COOMBS, of Charlottetown, in the Province of Prince Edward Island and Dominion of Canada, have invented a new and useful Improvement in Butter-Tubs, of which the following is a full, clear, and exact description.

The object of my invention is to furnish a tub especially adapted for packing butter for shipment, which tub cannot lose its hoops by their dropping off at the bottom, and from which tub the butter may be removed in bulk at the top, as usual.

My invention consists in certain novel features of construction, as hereinafter described and claimed.

Reference is to be had to the accompanying drawings, forming part of this specification, in which—

20 Figure 1 is a plan view of a stave of my tub lying on its outer face, and Fig. 2 is a sectional elevation of my improved tub.

A is the tub, formed of wooden staves *a*, and fitted with a bottom, *b*, and top or cover *c*, and bound with metal hoops *d*. The staves *a* are tapered lengthwise in thickness, and are placed together with their thicker ends at the bottom of the tub. The staves stand vertically—that is, so that a vertical plane would divide each 30 stave in thickness from its top completely to its bottom end. The outer or convex face of each stave is narrower at the top or thin end, and its inner or concave face is wider at the top or thin end than at the bottom or thick end. The bottom *b* of the tub is of a less diameter than the top *c*, so that the interior of the tub is of a greater diameter at the top. At the same time the tub is of greater diameter at the

bottom than at the top on the outside. The top *c* is fitted with a plug, *e*, which, on being removed, allows the butter to be inspected and sampled without removing the cover.

With this tub the butter can be packed with brine for foreign shipment, and the tub made water-tight, so that the brine cannot escape. 45 The external diameter of the top being the smallest, the hoops *d* can be loosened and the top *c* removed without turning the tub over. In case it is desired to remove the butter bodily from the tub, that is allowed by the 50 interior shape of the tub, which is of the largest diameter at the top.

This constitutes a cheap, safe, and convenient package for containing butter to be shipped to long distances.

It is to be understood that the staves taper in thickness only, they being uniform in width throughout their length.

Having thus described my invention, what I claim as new, and desire to secure by Letters Patent, is—

1. Staves for a tub or other vessel, thicker at one end than at the other, narrower at the thin end than at the thick end on one face, and wider at the thin end than at the thick 65 end on the other face, substantially as specified.

2. A stave-sided vessel smaller at the top than at the bottom outside, and larger at the top than at the bottom inside, substantially as 70 and for the purpose specified.

HENRY FREDRICK COOMBS.
